ATTORNEYS.

UNITED STATES PATENT OFFICE.

WILLIAM B. TURMAN, OF WALDRON, ARKANSAS.

PERMUTATION-PADLOCK.

SPECIFICATION forming part of Letters Patent No. 337,800, dated March 9, 1886.

Application filed October 3, 1884. Serial No. 144,640. (Model.)

To all whom it may concern:

Be it known that I, WILLIAM B. TURMAN, a citizen of the United States, residing at Waldron, in the county of Scott and State of 5 Arkansas, have invented certain new and useful Improvements in Combination-Locks, of which the following is a description.

Figure 1 is a front elevation of my improved lock. Fig. 2 is a side elevation of the same. 10 Fig. 3 is a section taken on the line *x* *x* in Fig. 2. Fig. 4 is a detail side view of the bolt and draw-bar. Fig. 5 is a plan view of the same. Fig. 6 is a plan view of the end plates removed from the frame, and Fig. 7 is an end 15 view of the same.

My invention has reference to combination-locks, which may be used as pad-locks or as door-locks; and it consists in the detailed construction and combination of the parts herein- 20 after fully described, whereby the said locks are arranged to open when in certain relative positions of their parts, which may be changed at will as often as desired, but which will not open unless in the particular position prede- 25 termined on.

Similar letters of reference refer to similar parts in all the figures.

A is the frame of the lock, B the bolt, and C the hasp engaging with the bolt and pivoted 30 in the frame on the pin *c*. D is the draw-bar by which the bolt is drawn back. E is the locking-bar for securing the bolt in its locked position.

The locking-bar E is turned around and 35 drawn back by the tumbler F, fastened on the end of it, which projects from the frame. The other end is made with a part, *e*, which enters a hole in the bolt B. A key, *e'*, prevents the locking-bar from being drawn backward, except when it is opposite the slot *a'* in the fixed bar *a* of the frame A.

A series of tumblers, G, H, and I, are arranged on the locking-bar and provided with letters or figures, and with alternating projections on their outer circumferences, so that they may be turned by the fingers to any position. The tumbler G has two disks—one on either side of it—of which the upper one, *g*, has figures or letters on its circumference, a central 45 hole larger than the locking-bar, and a guide-

ring, *g'*, to keep it in position. The hole in the tumbler G is also larger than the locking-bar, but the hole in disk *g'* fits it, and is provided with a slot, *g''*. The disks *g* *g'* are united to the tumbler G by one or more pins in the sides 55 of them which project into one or more of a series of corresponding holes in said tumbler G, so that the disks *g* *g'* and tumbler G may be made to occupy various relative positions, and the letters and figures on the circumference 60 of them may be made to form different combinations. The tumbler H has one disk, *h*, also united to it by one or more pins projecting therefrom into a series of holes in the side of it, so that different combinations of the tum- 65 bler and disk may be effected. The hole in the tumbler H is larger than the locking-bar, but the hole in disk *h* fits it, and is provided with a slot, *h'*. The tumbler I is similar to the tumbler H. The disk *i* is similar to the 70 disk *h*, and is provided with the slot *i'*.

The locking-bar E is further provided with keys *e* *e'* *e''* let into it which admit of its being revolved, when pushed up, as they then come in the larger central holes of the tumblers G 75 H I, but prevent the locking-bar from being drawn back unless the said keys come opposite to and can slide into the slots *g''*, *h'*, and *i'* of the disks *g'*, *h*, and *i*.

The tumblers and disks are kept in position 80 by the end plates, J and K, let into notches *a* in the frame A. These end plates form a bearing for the tumbler F, and have overlapping portions *j* and *k*, which are united together by screws or pegs *j'*. Letters or figures are 85 marked on the outside of the end plates, which form various combinations with other letters or figures on the circumference of the tumbler F, which is provided with a boss, *f*, on which it is journaled in the end plates, J 90 and K.

The tumbler F is secured in any desired position on the locking-bar E by a screw or pin, *f'*, preferably arranged to pass through the boss *f*, so that it may be out of sight when the 95 locking-bar is pushed up.

The bolt B, which is secured in position by the locking-bar, may be made of one piece; but I generally prefer to make it in two parts, as shown in the drawings, so that the hasp C 100

may engage with it automatically when shut down. When made in two parts, one of them, *b*, serves as the bolt which engages with the hook *c* on the end of the hasp *C*. The second 5 part, *b'*, slides within it, and is provided with a hole to receive the end *e* of the locking-bar, and with a slotted portion, *b*², for receiving the end of the draw-bar *D*. The part *b'* is formed with flanges *b*³, sliding in the grooves 10 *b*⁴ in the part *b*. The two parts *b* and *b'* have the spring *b*⁵ arranged between them, so that when the hasp of the lock is pressed down the curved lower side of the hook *c* pushes back the part *b* of the bolt against the pressure of the spring *b*⁵ and automatically engages 15 itself, but cannot be disengaged again without a knowledge of the combination at which the lock has been set.

The draw-bar *D* is provided with an end, 20 *d*, engaging with the slotted portion *b*² in the bolt, in which it turns freely, but cannot be moved endwise without also moving the bolt. A key, *d'*, projects from the side of the draw-bar. A head, *d*², is fastened on the end of the 25 draw-bar, and is provided with letters or figures on its circumference alternating with projections for turning it round with the fingers.

A sleeve, *L*, is journaled in the frame *A*, 30 and provided with a slot, *l*, and a groove, *l'*. A pin, *l*², is driven through the sides of the frame *A*, so as to pass through the groove *l'* at one point. This pin keeps the sleeve *L* from moving endwise, but leaves it free to turn. 35 The end *l*³ of the sleeve *L*, which projects through the frame, is made many-sided and provided with a tumbler, *M*, fitting loosely upon it and having projections on its circumference for turning it round alternately with 40 letters or figures.

An index-letter, *N*, is situated on the outside of the frame, and a slot, *P*, is formed at one point of the bearing in frame *A* corresponding with that in the sleeve *L*. The key 45 *d* is made long enough to engage with both of the slots *l* and *P* at once when they are brought into line and the draw-bar *D* is drawn back.

The frame *A* is made with a detachable part, 50 *a*³, firmly secured thereto by the rivets *a*⁴. Index-letters *R* are also marked on the frame and on the loose part *a*³ in connection with the disk *g*.

In order to withdraw the locking-bar *D*, 55 which secures the bolt, the tumblers *G*, *H*, *I*, and *F* must be turned relatively to the frame *A* and to one another, so that the keys *e*, *e*², *e*³, and *e*⁴ may simultaneously slide into their respective slots *a*², *g*², *h*², and *i*² when the locking-bar is pulled back. This position is indicated by a certain combination of the letters and figures which then come into line, and can be variously arranged and altered from time to time by changing the relative positions of the tumblers *G*, *H*, and *I* with regard to their accompanying disks and the positions of the tumbler *F* with regard to the

figures on the end plates. The locking-bar *E* being drawn back, the draw-bar *D* and tumbler *M* must next be rotated until they 70 are in such a position with regard to the frame *A* that the key *d*' can slide into the slots *l* and *P*. This position is indicated by a certain combination of letters and figures on the tumbler *M* and head *d*², which then come into 75 line with the index-letter *N* on the frame and with one another. This combination can be variously altered by changing the position of the tumbler on the sleeve *L*. When the key *d*' can slide into the slots *l* and *P*, the draw-bar *D* can be drawn back, and with it the bolt *B*, thus relieving the hasp *C*, with the hooked end of which the said bolt engages.

My combination-lock can be modified to 85 make it suitable for doors of safes or shutters by leaving off the hasp and its attachments and continuing the bolt *B* through the side of the frame, as indicated by the dotted lines in Fig. 3, so that it may engage with a plate let into the door-post, which then takes the 90 place of the hasp.

Another simple modification of my invention consists in leaving out the locking-bar *E* and all that portion of the frame below the fixed bar *a*. It then forms a simple combination-padlock, which is suitable for a great 95 many places.

When the locking-bar is used, the number of tumblers and disks may be increased or diminished as required.

Having thus described my invention, what I claim as new, and desire to secure by Letters Patent, is—

1. The combination of the part *b*, having grooves *b*⁴, with the part *b'*, sliding within it 105 and having a slotted portion, *b*², and flanges *b*³, and the spring *b*⁵, forming the bolt *B* of the lock, substantially as described and shown, and for the purpose set forth.

2. The combination of the draw-bar *D*, 110 having a key, *d'*, and a head, *d*², with the sleeve *L*, provided with the slot *l*, groove *l'*, and the many-sided projecting end *l*³, the pin *l*², for retaining said sleeve in frame *A*, the tumbler *M*, and frame *A*, having the slot *P* 115 and index-letter *N*, substantially as described, shown, and set forth.

3. The combination of the bolt *B* when made in two parts, *b* and *b'*, substantially as described, and provided with a spring, *b*⁵, with 120 the draw-bar *D*, having the key *d'* and head *d*², the sleeve *L*, having the slot *l* and many-sided end *l*³, the tumbler *M*, and frame *A*, having the slot *P* and index-letter *N*, substantially as described, shown, and set forth. 125

4. The combination, with the frame and locking-bar *E*, having a key, *e*², of the tumbler *G*, having a central aperture, through which the locking-bar and its key may freely pass, and two disks on opposite sides of the tumbler and connected to it by holes and pins, one of the disks having a central aperture of greater diameter than the locking-bar and its key, and the other disk having a smaller ap-

erture and a notch in the wall of the same, substantially as set forth.

5. The combination of tumbler G, having disks g and g', the tumbler H, having disk h, the locking-bar E, provided with the keys e', e², and e³, and the frame A, provided with the fixed bar a, having a slot, a', and the index-figures R, substantially as described and shown.

6. The combination of the locking-bar E, provided with an end, e, engaging with a hole in the bolt B, and the key e', the tumbler F, provided with a boss, f, and screw f', the end plates, J and K, provided with overlapping portions j and k, united by the screws j', and the frame A, provided with the fixed bar a, having a slot, a', the index-figures R, and notches a², for receiving the end plates, substantially as shown and described.

7. The combination of the hasp C, bolt B, made in two parts, the draw-bar D, provided with the sleeve L and tumbler M, the locking-bar E, provided with a series of tumblers, F, G, H, and I, the end plates, J and K, united by the screw j', passing through their overlapping portions j and k, and the frame A,

provided with the fixed bar a, notches a², slots a' and P, and index-letters N and R, substantially as described and shown, and for the purpose set forth.

8. The combination, with the lock-frame 30 and a sliding bolt, of a perpendicular movable locking-bar at right angles to the sliding bolt, adapted to engage the said bolt with its upper end, and provided with a tumbler projecting through the frame and having characters on 35 its periphery, the lower end of the locking-bar projecting through the frame, substantially as set forth.

9. The combination, with the lock-frame open at its bottom, the walls of the opening 40 being recessed at a², and the locking-bar E, extending through the same, of the end plates, J K, having overlapping portions j k, secured together and recessed to form an aperture for the locking-bar to pass through.
